X-RAY FILM DEVELOPING MACHINE

Henry F. Hope, 3192 Huntingdon Road, Huntingdon Valley, Pa. 19006, and Stephen F. Hope, 2548 Wyandotte Road, Willow Grove, Pa. 19090

Filed Dec. 21, 1973, Ser. No. 427,350

Term of patent 14 years

Int. Cl. D16—03

U.S. Cl. D61—1 Q

FIG. 1

FIG. 2

FIG. 5

FIG. 6

FIG. 1 is a perspective view of an X-ray film developing machine showing our new design.

FIG. 2 is a top plan view thereof.

FIG. 3 is a right side elevational view thereof.

FIG. 4 is a rear elevational view thereof.

FIG. 5 is a left side elevational view thereof.

FIG. 6 is a front elevational view thereof.

We claim:

The ornamental design for an X-ray film developing machine, as shown.
